UNITED STATES PATENT OFFICE.

ELMER G. BURNS, OF LOS ANGELES, CALIFORNIA.

VACUUM TANK.

Application filed May 9, 1927. Serial No. 189,944.

My invention relates to vacuum tanks as used in feeding systems for supplying gasoline or other fuel to carbureters of internal combustion engines for motor vehicles.

5 It is a purpose of my invention to provide a vacuum tank characterized by simplicity of construction and consequent low cost of manufacture and more particularly with reference to the simplicity of the mechanism 10 for actuating the suction and air valves through the medium of the float in such manner that closing and opening of the valves in the proper sequence is effected with a degree of positiveness as to insure fluid 15 tight seating and to prevent sticking of either valve in closed position.

It is also a purpose of my invention to provide a vacuum tank constructed to permit of its direct association with and mounting 20 on a conventional form of carbureter to eliminate the separate and remote mountings and the necessary connections as now required with present vacuum tanks.

I will describe only one form of vacuum 25 tank embodying my invention and will then point out the novel features thereof in claims.

In the accompanying drawings:

Figures 1 and 2 are views showing a 30 vertical section one form of vacuum tank embodying my invention and illustrating the two extreme positions which the movable parts thereof occupy during the operation of the tank;

35 Figure 3 is a view showing in top plan and partly in section the vacuum tank shown in the preceding views;

Figure 4 is a view showing the vacuum 40 tank in side elevation with portions thereof broken away to reveal parts not otherwise disclosed.

Referring specifically to the drawings, my invention in its present embodiment, comprises a receptacle or tank 15 provided with 45 a cover 16 closing the upper open end of the receptacle, the receptacle being provided interiorly with an arcuate partition 17 dividing the receptacle into a float chamber 18 and a reservoir chamber 19. The partition 17 is 50 provided with a depending extension 20 having a port 21 through which the passage of gasoline or other liquid fuel from the chamber 18 to the chamber 19 is controlled by a flapper valve 22. This valve is accessible 55 through an opening normally closed by a screw plug 23 having a tongue 24 positioned

to function as a stop in defining the open position of the valve.

As illustrated to advantage in Figures 3 and 4, the receptacle is provided with an extension or arm 25 which is tubular and in communication with the reservoir chamber 19. This arm extends laterally from the receptacle adjacent the bottom thereof and at its outer end is provided with a vertical 60 or transverse opening 26 designed to receive the usual depending tubular extension 27 of any conventional carbureter, as well as the usual screw plug 28. As the extension 27 is formed with openings, the extension 25 65 being tubular provides communication between the mixing chamber of the carbureter and the reservoir chamber of the receptacle in order to permit the feeding of gasoline from the vacuum tank to the carbureter. 70 This construction provides simple and effective means by which the vacuum tank as a unit can be directly attached to and supported on the conventional carbureter in contradistinction to the provision of a separate mounting for the vacuum tank and at a point remote with respect to the carbureter, 75 as is now the practice.

The cover 16 is constructed to provide a port 29 adapted for connection to the usual 80 gasoline line by which gasoline from the supply tank is conducted to the vacuum tank. At the inner end of this port is arranged a plate 30 for the purpose of deflecting the gasoline entering the float chamber against 85 one wall thereof and in a manner to prevent the gasoline from being discharged directly onto the float and thus interfering with the proper operation of the latter. The cover 90 is also constructed to provide a duct 31 adapted for connection to the intake manifold of an internal combustion engine through the usual pipe (not shown). The inner end of this duct communicates with a second duct 32 in which is positioned a valve 95 seat 33 having a central opening which constitutes a suction port through which air from the float chamber is sucked to create a negative pressure or partial vacuum within the float chamber when the vacuum tank 100 is connected to the intake manifold of the engine, as will be understood.

The cover 16 is provided with a suitable 105 opening 34, the wall of which is screw-threaded to receive a plug 35 having a duct 36. The second plug 37 is threaded in the first plug and is constructed to receive and

support a vent pipe 38, the latter communicating at its inner end with the duct 36 and the inner end of the duct being constructed to provide a port, which will be hereinafter referred to as an air port. It is important to note that the ports 33 and 36 are disposed one above the other or oppositely in order to accommodate therebetween and permit the desired operation of a stem 39. The opposite ends of this stem are constructed to provide a suction valve 40 and an air valve 41 for the respective ports 33 and 36. At the inner ends of the valves the stem is provided with annular flanges 42 and 43 adapted to be engaged by a lever 44 for moving the stem to open or close either of the valves 40 and 41. As shown in Figure 3, the lever 44 is of U form and is fulcrumed between its ends on a pin 45 extended into the cover 16 and having a screw head 46 threaded in the cover. The free ends of the lever 44 extend to opposite sides of the stem 39 at a point between the flanges 42 and 43, and the mounting of the lever is such that it is capable of occupying either of two extreme positions. In one extreme position it engages the flange 42 to move the suction valve 40 to closed position and the air valve 41 to open position. In the other extreme position, the lever engages the flange 43 to move the air valve 41 to closed position and the suction valve 40 to open position. In view of the spacing of the flanges 42 and 43, it will be understood that the stem is actuated during the latter part of the movement of the lever in either direction, the major movement of the lever being what may be termed lost motion, but intentional, for a purpose to be described hereinafter.

40 Fulcrumed at one end on the lever 44 is a second lever 47 adapted to be moved to either of the two extreme positions by a float 48 in the chamber 18, the float being operatively connected to the other end of the lever 45 through a rod 49. In order to permit the lever 47 to move to its upper extreme position, a portion thereof is bent in the form of a U, as indicated at 47^a, in order to clear the pivot pin 45. A flat arcuate spring 50 is loosely mounted at one end on a pin 51 extended into the cover 16 and provided with a screw head 52 for retaining the pin in proper position. The opposite end of the spring is connected to the lever 47 at a point between the ends of the latter and through the medium of a pin 53. The lever 47 is preferably of U form in order to provide the desired strength and to facilitate its connection with the other lever and float rod.

45 The lower side of the float 48 is provided with the usual depending stem 54 which may be a continuation of the rod 49 and which is movable through an opening 55 in the bottom of the receptacle, in order to

properly guide the float in its vertical movements. This opening 55 is in communication with a chamber 56 normally closed by a plug 57. A second plug 58 is threadedly fitted in the bottom of the receptacle, and these two plugs 57 and 58 may constitute drain plugs by which the receptacle can be drained of water and sediment.

The operation of the vacuum tank is as follows: With the parts of the apparatus in the position shown in Figure 2 and the duct 31 connected to the intake manifold of an engine, the suction valve 40 being in open position permits the exhaustion of air from the chamber 18, causing gasoline to flow into the chamber through the port 29. As the level of liquid rises, the float 48 moves upwardly, acting through the rod 49 to move the lever 47 upwardly to the position shown in Figure 1. During this movement, the lever swings about its fulcrum point, the lever 44 remaining stationary until the pivot 53 passes above the pivot 41, when the spring 50 will act through the lever 47 to rock the lever 44 to the position shown in Figure 1. Under this movement of the lever 47, the flange 42 is struck by the free end of the lever, thus suddenly and rapidly moving the suction valve 40 to closed position and the air valve 41 to open position. The operation of the lever 44 is such as to cause the valve 40 to firmly seat and thus effectively close the suction port 33. Conversely, the lever operates to open the air valve 41 with a force sufficient to overcome any tendency to stick and in this manner the movement of the valves to open or closed position is rendered positive.

With the suction valve closed and the air valve open, the suction action is discontinued and the float chamber placed in communication with atmosphere to cause gasoline to be discharged from the chamber into the reservoir chamber 19. As gasoline is dispensed from the reservoir in accordance with its consumption by the carburetor, the float 48 moves downwardly with the lowering level of the liquid and, through the medium of the rod 49, the lever 47 is drawn downwardly against the tension of the spring 50 until the pivot 53 passes by the pivot 45, when the spring will react through the lever 47 to suddenly move the lever 44 to the position shown in Figure 2. In this position of the lever, it engages the flange 43, thereby elevating the stem 39 to suddenly open the suction valve 40 and close the air valve 41. Thus the float chamber is again placed in communication with the intake manifold to permit suction to act in refilling the float chamber.

It is important to note that in either extreme position of the lever 47 the spring 50 operates to urge the lever to either position and that as the lever passes what may be

termed dead center with respect to the pivot 45 the spring acts reversely to suddenly move the lever 44 to either of its extreme positions. In this manner, initial movement 5 of the lever 47 is rendered ineffective to actuate the lever 44, resulting in the sudden actuation of the lever to secure the desired positive opening and closing of the suction and air valves.

10 Although I have herein shown and described only one form of vacuum tank embodying my invention, it is to be understood that various changes and modifications may be made therein without departing from the 15 spirit of the invention and the spirit and scope of the appended claims.

I claim as my invention:

1. A vacuum tank comprising a receptacle having a float chamber and a laterally disposed reservoir chamber, a port providing communication between the two chambers, a flapper valve controlling the port, a tubular and laterally disposed extension on the receptacle having a transverse opening 25 adapted to receive the depending extension of a carburetor, a float in the float chamber, a cover for the receptacle having a fuel port, an air port and a suction port, a rod for the float, a lever mounted on the cover, 30 a second lever fulcrumed on the first lever and connected to the float rod, a flat spring connected to the second lever at a point between its connections with the first lever and float rod, a stem having on one end a 35 suction valve for the suction port and on the other end an air valve for the air port, flanges on the stem, and arms on the first lever disposed between the flanges to engage one or the other in moving the stem to 40 actuate the valves.

2. In a vacuum tank, oppositely disposed suction and air ports, valves therefor, a stem common to the valves and movable to open or close one valve or the other according 45 as the stem is moved in one direction or the other, and float operated mechanism for actuating the stem comprising a pair of levers, one fulcrumed on the other and adapted for connection to the rod of a float, 50 the other fulcrumed on a fixed axis eccentric with respect to the fulcrum of the first mentioned lever and operatively connected to the stem, and a spring engaging the first lever for the purpose described.

55 3. In a vacuum tank, oppositely disposed suction and air ports, valves therefor, a stem common to the valves and movable to open or close one valve or the other according 55 as the stem is moved in one direction or the other, and float operated mechanism 60 for actuating the stem comprising a lever

operatively connected to the stem and fulcrumed between its ends to occupy either of two extreme positions in which the stem is engaged by one end of the lever and 65 moved in one direction or the other, a second lever fulcrumed at one end on the other end of the first lever, the other end of the second lever adapted for connection to a float rod for movement thereby to either of 70 two extreme positions, and a spring mounted and connected to the second lever between the ends of the latter to urge the second lever to either extreme position and in such manner that as the second lever passes 75 beyond a medial position when moving in either direction it will effect a succeeding and rapid movement of the first lever from one extreme position to the other.

4. In a vacuum tank, oppositely disposed 80 suction and air ports, valves therefor, a stem common to the valves and movable to open or close one valve or the other according as the stem is moved in one direction or the other, and float operated mechanism for actuating the stem comprising a lever operatively connected to the stem to occupy either of two extreme positions in which the stem is moved in one direction or the other, a second lever fulcrumed on and at 85 a point eccentrically with respect to the first lever and adapted for connection to a float rod for movement thereby to either of two extreme positions, and a spring connected to the second lever for urging the latter to 90 either extreme position and in such manner that as the lever passes beyond the medial position when moving in either direction will effect a succeeding and rapid movement 95 of the first lever from one position to the 100 other.

5. In a vacuum tank, a suction valve, an air valve, a stem common to the two valves, and by movement of which one valve is opened while the other is closed, and means for actuating the stem comprising a pair of levers, one of which is operatively associated with the stem and is fulcrumed about a fixed axis and the other fulcrumed on the first mentioned lever at a point eccentric with respect to the fulcrum of the latter and adapted for operative connection to the rod of a float, and a resilient means engaging the last mentioned lever for the 105 purpose described.

6. The combination as embodied in claim 5 wherein said resilient means comprises a flat spring flexed into curved form and fixed against movement at one end while its other end is connected to the last mentioned lever.

ELMER G. BURNS.
